UNITED STATES PATENT OFFICE

162,379

SUIT

Toni Carnegie, New York, N. Y.

Application November 18, 1950, Serial No. 13,051

Term of patent 3½ years

(Cl. D3—4)

To all whom it may concern:

Be it known that I, Toni Carnegie, a citizen of the United States, residing in the city of New York, in the county of New York and State of New York, have invented a new, original, and ornamental Design for a Suit, of which the following is a specification, reference being had to the accompanying drawing, forming part thereof:

Fig. 1 is a front view of a suit showing my new design.

I claim:

The ornamental design for a suit, substantially as shown.

TONI CARNEGIE.
